UNITED STATES PATENT OFFICE

EDGAR J. BLOOM, OF TIFFIN, OHIO

CLOTHES RACK

Application filed October 21, 1927. Serial No. 227,749.

This invention relates to a clothes rack utilizing side frames of the lazy tongs type connected by cross rods.

The primary object of the invention is to provide an extensible rack of this type which can be shipped in a knock-down condition and subsequently assembled readily, the parts, when once assembled, being held together permanently and firmly so that the rack will not sag or come apart.

Racks of the kind mentioned have heretofore been made in knock-down form but in view of the different lengths of cross rods necessarily employed, it has frequently happened that, when the racks have been assembled, short rods have been placed where long rods should be located and, as these rods have been locked in place as soon as assembled, the rack when set up for use has been distorted and unfit for sale. Consequently great care has been necessary heretofore in assembling the parts to avoid placing them in wrong positions.

It is an object of the present invention to form the rack with cross rods of uniform length so that any rod can be placed in any position when the rack is assembled and, consequently, there is no danger of making a wrong assembly of the parts.

A further object is to provide a rack of increased strength due to the fact that the pivotal connections between the members of the side frames are of minimum size, requiring holes of much less diameter than have heretofore been utilized where the cross rods have been extended directly into the joints between the frame members.

A further object is to provide the rack with locking means for holding the cross rods to the side frame, these locking means being located entirely outside of the frame members so that a strong structure can thus be produced.

With the foregoing and other objects in view which will appear as the description proceeds, the invention resides in the combination and arrangement of parts and in the details of construction hereinafter described and claimed, it being understood that changes in the precise embodiment of the invention

herein disclosed may be made within the scope of what is claimed, without departing from the spirit of the invention.

In the accompanying drawings, the preferred form of the invention has been shown.

In said drawings,

Figure 1 is a perspective view of a clothes rack embodying the present improvements.

Figure 2 is an enlarged section through one of the joints of the rack, showing one end of a cross rod locked to one of the pivots of one side frame.

Figure 3 is a section through one side frame showing a connection between one of the cross rods and one of the side frame members at a point where one thickness only of the side frame is provided.

Figure 4 is a section on line 4—4, Figure 3.

Figure 5 is a section through one of the locking caps or ferrules which may be used for holding a cross rod to a side frame.

Figure 6 is an end view of said cap or ferrule.

Figure 7 is a side elevation of one of the combined pivots and dowels.

Referring to the figures by characters of reference 1 designates the uprights of a side frame of the rack, these uprights being connected by a lazy tong connection consisting of crossed strips 2 and 3 pivotally connected at their points of crossing, the strips 2 which extend from the upper ends of the standards 1 being longer than the remaining strips 3. It is to be understood, however, that any desired arrangement of pivotally connected strips can be used, it merely being necessary to have them assembled in such a way that the frame can be collapsed by moving the uprights 1 toward each other and extended by moving them from each other. Two of these side frames are employed, these frames being both of the same construction. The members of each frame are connected by pivot pins 4 the outer ends of which are adapted to be upset or headed as shown at 5, washers 6 being preferably employed for engagement by the heads of the pivot pins. Each pin has a shoulder 7 extending therearound, the distance between this shoulder and the head 5 of the pin being equal to the thickness of two

100

frame members. Extending from the shouldered end of each pin is a dowel 8 the diameter of which is preferably somewhat greater than that of the main portion of the pin 4, there being an annular groove 9 at the base of the dowel as shown. At those points where the frame members 2 and 3 are in lapped relation and where these members lap the standards 1 the pivot pins 4 extend through the lapping members and form firm connections therebetween. The dowels 8 of the pins are adapted to project into bores 10 formed in the ends of cross rods 11, each bore being counterbored at 12, and extending into a cap or ferrule 13 having a central opening 14 for the reception of the dowel and the shoulder 7. Prongs 15 are pressed inwardly in the formation of the opening 14 and are designed, when the rods 11 are placed in position on the dowels, to snap into the annular groove 9, thereby locking the rods to the pins 4 and preventing the parts from being separated. The ferrules can be held to the rods 11 in any well known manner, as by forming spaced depressions in the ferrules after they have been fitted tightly on the rods 11. This means of attaching the ferrules is so obvious that it is not deemed necessary to show the same.

It is designed to use rods 11 of one length only. Thus at those points where cross rods are employed and only one thickness of material is provided in the frame of the rack, it is necessary to employ a spacing disk 16 through which the pivot pin 4 is extended.

This spacing disk is of the same thickness as the frame members and acts as a filler to compensate for the excessive length of the pivot pin where it is extended through one thickness only of the frame of the rack. At some points it is essential that these filling disks be placed on the inner sides of the frames of the rack, as shown for example in Figure 3. At other places, however, it is necessary that the disks be located on the outer sides of the frame. Disks positioned in this manner have been indicated at 17 in Figure 1.

It is to be understood that the pivot pins, frame members and spacing disks are assembled in proper relation to each other at the factory. The rods 11 are all cut to the same lengths and have their ends finished the same way. The parts are bundled into compact form and shipped to the merchant who assembles them simply by forcing the ends of the rods onto the projecting dowels, the parts 15 and 9 cooperating to lock the rods to the dowels. It will be noted that the dowels 8 have close fitting engagement in the bores 10 and the ends of rods 11 have a similar fit in the caps 13 so that when the rods, caps and dowels are assembled they remain in position. If additional securing means are desired, holes may be provided in caps 13 for brads to be driven into the rods or a prick punch may be used to indent the caps 13 and form project-

ing portions which extend into the rods 11, or any other suitable securing means may be employed. As all of the rods are of the same length there is no danger of placing them in wrong positions. Consequently the rack can be easily assembled by any one. As the pivot pins 4 are of small diameter, it is only necessary to form small openings in the frame members to receive these pins. Consequently these frame members are not weakened as would be the case should it be necessary to provide large bores for the reception of the cross rods.

Although the rods have been shown locked to the pivot pins by the specific means described, it is to be understood that any other means may be utilized for this purpose.

What is claimed is:

1. A collapsible knock-down rack including frame members each consisting of uprights and lazy tong connections between the uprights, pins extending through the side frames, certain of said pins constituting pivotal connections between the members of the frames, a dowel at one end of each pin, all of the pins and their dowels being of the same size, cross rods having recessed ends for the reception of dowels, all of the cross rods being of the same length, and cooperating means upon the cross rods and dowels for locking said rods to the dowels.

2. A collapsible knock-down rack including end frames each comprising standards and a lazy tong connection between the standards, pins extending through the end frames, certain of said pins constituting the pivotal connections between the members of the end frames, a dowel at one end of each pin, all of the pins with their dowels being of the same size, spacing elements upon certain of the pins for holding the dowels of said pins projected inwardly from the frame the same distance as the dowels of the other pins, cross rods of uniform lengths for engagement with corresponding dowels on the opposed frames, and cooperating means upon the cross rods and the dowels for locking said rods to the dowels.

3. A collapsible knock-down rack including end frames each comprising standards and a lazy tong connection between the standards, pins extending through the end frames, certain of said pins constituting the pivotal connections between the members of the end frames, a dowel at one end of each pin, all of the pins with their dowels being of the same size, spacing elements upon certain of the pins for holding the dowels of said pins projected inwardly from the frame the same distance as the dowels of the other pins, cross rods of uniform lengths for engagement with corresponding dowels on the opposed frames, and cooperating means upon the cross rods and the dowels for locking said rods to the

dowels, said means being located entirely without the frame.

4. A knock-down rack including frames made up of suitably connected members, pivot pins extending through the members, 5 all of the pins being of the same size, certain of said pins constituting pivotal connections between the members, spacing means upon the other pins for holding them projected from the frame the same distance as the pivot pins, cross rods all of the same length, dowels carried by the pins for engagement by the ends of the cross rods, and cooperating means upon the cross rods and dowels and 10 wholly outside of the frame for locking the cross rods to the dowels.

5. A knock-down rack including end frames each comprising standards and a lazy tong connection between the standards, 20 a plurality of rods all of the same length insertible between the end frames, and means projecting from the end frames for engaging the outer surface of and a bore within the ends of the rods to lock said rods to the 25 frames.

6. A knock-down rack including end frames each comprising standards and a lazy tong connection between the standards, a plurality of rods all of the same length 30 insertible between the end frames, and means of uniform length projecting from the end frames for engagement in bores in the ends of the rods, and other means disposed between the ends of the rods and the end 35 frames and having flanged portions of uniform length for closely engaging the outer surfaces of the ends of the rods.

7. A collapsible rack comprising foldable standards composed of pivoted members 40 disposed in side by side engagement, pivot pins of small diameter extending through adjacent pairs of said members and having enlargements disposed on the outer sides of each pair of said members to retain them 45 in assembled relation, each of the pins extending at one end beyond the adjacent member and provided with a shouldered recess, perforated elements engaging the recesses, and rods of uniform length having 50 bores at either end to receive the extensions of the pins.

8. A collapsible rack comprising foldable standards composed of pivoted members disposed in side by side engagement, pivot pins 55 of small diameter extending through adjacent pairs of said members and having enlargements disposed on the outer sides of each pair of said members to retain them in assembled relation, each of the pins extending 60 at one end beyond the adjacent member and enlarged and provided with a shouldered recess, perforated flanged discs engaging the recesses on the pins, and rods of uniform length having bores to receive the extensions 65 of the pins with close fitting engagement and

extending into and having close fitting laterally supported engagement in the flanged portions of the discs.

In testimony that I claim the foregoing as my own, I have hereto affixed my signature. 70
